The ornamental design for a one-handed device activation apparatus, as shown and described.

DESCRIPTION

FIG. 1 is a front isometric view of an ornamental design for a one-handed device activation apparatus;

FIG. 2 is a front elevation view thereof;

FIG. 3 is a rear elevation view thereof;

FIG. 4 is a top plan view thereof;

FIG. 5 is a bottom view thereof;

FIG. 6 is a right side elevation view thereof;

FIG. 7 is a left side elevation view thereof; and,

FIG. 8 is a front isometric view thereof, showing a device, for example, a camera, positioned between adjoining gripping members of the one-handed device activation apparatus.

The broken line showing of a fastener in FIGS. 1-8, the camera in FIG. 8, and the symbol "K" in FIG. 1, FIG. 4, and FIG. 8 is for the purpose of illustrating environment and forms no part of the claimed design.

The mark "KNEKT" forming a part of the claimed design is a trademark applied for registration, having U.S. Trademark Ser. No. 86169829, and owned by KNEKT Industries Ltd.
